UNITED STATES PATENT OFFICE

FRANCIS J. PLYM, OF NILES, MICHIGAN, ASSIGNOR TO THE KAWNEER COMPANY, OF NILES, MICHIGAN, A CORPORATION OF MICHIGAN

WINDOW CONSTRUCTION

Original application filed June 21, 1923, Serial No. 646,716. Divided and this application filed June 24, 1927. Serial No. 201,058.

My present invention relates to metallic window constructions and more particularly to those in which the sashes are slidable vertically with respect to the frames and among the objects of my invention are to provide an improved sash construction and particularly for the meeting rails whereby a more effective weather seal is formed and whereby the window panes are effectively and more conveniently held in position and whereby a locking mechanism for the window sashes may be mounted upon and cooperate with the meeting rails to hold the sashes locked and to provide such further objects, advantages, and capabilities as will later more fully appear and are inherently possessed by the invention.

My invention further resides in the combination, construction and arrangement of parts illustrated in the accompanying drawings and, while I have shown therein a preferred embodiment of my invention, I desire the same to be understood as illustrative only and not as limiting this invention.

In the drawings annexed hereto and forming a part hereof Fig. 1 is a broken elevation of a window embodying my present improvements; Fig. 2 is a broken horizontal section substantially along the plane indicated by the line 2-2 Fig. 1; Fig. 3 is an enlarged view of the lock shown in Fig. 1; Fig. 4 is a broken vertical section substantially along the plane indicated by the line 4-4 Fig. 1;

Referring more in detail to the annexed drawings, numeral 1 denotes in general the window casing or frame and numerals 2 and 3 the lower and upper sashes, respectively. The frame comprises a pair of side members 4, a head member 5 and a sill 6, the side members having as a part thereof the pulley stiles 7 and the head member 5 having the head jamb 8. The side members 4 are made up of a plurality of members, as shown more clearly in Fig. 2, where the pulley stile 7 is shown as being folded over to interfit closely and cooperate with another member, as shown at 9, to form a tight connection and weather seal. An edge 10 is bent outwardly to provide a projection under

which a flange 11 of a removable plate 12 may be inserted. The opposite edge of this plate 12 is folded over so that it may be inserted in a groove formed by similarly folding an edge of the pulley stile 7. This forms a tight connection at this point but still leaves it possible to separate the cap plate 12 by the removal of screws 14 which may be of any desired number, two being shown in the drawings. Upon removal of the plate 12 it will be possible to have access to the weights 15 so that they may be easily removed or put in place when desired. A plate 16 is hinged to one interior wall of side member 4 and may be held in proper position by means of springs or otherwise, as desired. After the plate 12 has been removed and the first weight 15 taken out of the opening in the casing, it will be possible to swing the plate 16 out of the way so that the other weight 15 may be brought out through the opening made by the removal of plate 12. It will be understood that the weights 15 may be cylindrical, as shown, or rectangular in cross section or may have other desired shapes. Whatever shape is selected, the hinged plate 16 serves as a separator to keep the weights from interfering by striking each other.

Near their upper portions, the pulley stiles 7 have portions punched out as indicated at 17 to form the hooks 18 by means of which the pulley casings 19 are held in place. Pulleys 20 are carried by shafts 21 within these casings and over the pulleys pass sash cords 22 which are attached at one end to the sashes and at the opposite end to sash weights 15. In applying the pulley casings 19 to the frame, the hooks 18 are punched out at right angles to the pulley stiles 7 and then passed through openings in flanges of the casings 19. After the casings are in place the hooks 18 are bent up and down, respectively, to hold the casings in place.

As shown in Fig. 2, the pulley stiles 7 are folded during the forming process to form two pairs of grooves as indicated at 24. In this figure the numeral 25 denotes (by dotted lines) the positions of the pul-

leys 20 and their casings 19. It will thus be seen that each of these casings fits in between a pair of grooves 24 and that the cords 22 coming down from the pulleys 20 will be in position to be attached to the sashes. In the case of the lower sash, any suitable means 26 is used to fasten the rope 22 to the top of the sash, while, in the case of the upper sash, the rope passes through an opening in the top edge thereof and down to a suitable securing means, such as a pin 27 which should be far enough below the level of the axle or shaft 21 not to interfere with the pulley when the sash is raised to its uppermost limit. It will be understood from this that there should be an opening in the upper corner of the sash of sufficient size to pass the pulley as the sash is raised. If desired, the parts may be welded together at 9 or reliance may be placed entirely upon a close fit to prevent moisture and wind from passing through this joint. It is preferable, however, that side members 4, head member 5 and sill 6 should be welded into a unitary whole. Similarly, the side, top, and bottom members of the sashes are welded at the corners to form a unitary construction. The head jamb 8 is provided with a pair of grooves 28 for the reception of the doubled edges 29 of the head rail 30 of the upper sash. In this connection it will be noted that the head rail or top rail 30 of the upper sash, the lower rail 31 of the lower sash and both side rails of both sashes are entirely open along the edge directed away from the glass. It will thus be seen that the construction of all the outer rails of the sashes is the same. While the meeting rails 32 and 33 are not absolutely identical, as shown, they are substantially so and could, if desired, be made identical. Each of the rails is provided with an abutment 34 formed by appropriate bending of the sheet metal from which the rails are made. Each rail is formed with a groove or pocket 35, formed by bending the metal appropriately, for the reception of one edge 36 of the glass stop 37, a part 38 of which rests against the glass to hold it tightly in place. It will be seen by reference to Fig. 4 that parts 36 and 38 are offset slightly relatively to each other, the purpose of this being pointed out later. Referring more particularly to the lower part of Fig. 1, it will be seen that there is a lower glass stop 39, two lateral stops 40 and an upper stop 41. Assuming that the building has been erected and, during the process of erection, the frame and sashes have been put in position, it will be seen that the sashes are ready to receive the glass 42. After this has been put in position the lower stop 39 is inserted into position by having its portion 36 inserted in the groove 35. Side stops 40 are then put in place in

the same manner, thereby locking stop 39 in place. Stop 41 has its portion 38 so cut that it will fit in between the stops 40 and it can, therefore, be shoved upwardly into place, portion 36 going into the groove 35. The part 36 of the upper stop 41 as well as the meeting rail 33, is provided with holes for the reception of screws 43 whereby stop 41 is held in place. Since the parts 36 and 38 are not in the same plane, it is possible for part 36 of stop 41 to rest on part 38 of stops 40 while being put into place, but this would be very troublesome if the two parts were not offset laterally from each other. The construction of the upper sash is similar to that of the lower sash.

It will be understood that the glass in both of these sashes may be unitary as well as made in a plurality of pieces, as shown in the drawings. When a plurality of lights of glass are used, muntins or mullions 44 are used to cover the junction between the glasses, as shown in Fig. 2. These mullions comprise outer and inner plates which are secured together by means of a plurality of bolts 45, provided with suitable nuts, as shown in Fig. 2. In setting the glass, use is made of a suitable sealing material 46, for example, putty. This prevents wind and water from passing in between the glass and its mounting, as well as aiding in preventing rattling of the glass.

The sill 6 is provided with a ridge 47 in the plane of the lower sash, as shown in Fig. 3, so that the two sides of the lower rail 31 may come down and engage tightly on opposite sides of this ridge to form a tight joint therewith. The lower rail is provided with one or more handles 48 secured thereto in any desired manner. By means of these the sash can be raised and lowered quite readily.

The meeting sash rails 32 and 33 are provided with a locking device comprising a member 49 suitably secured as by welding in the extension 50 of rail 32 and extending upwardly through an aperture provided in the upper wall of this extension. The protruding portion of the member 49 is of such a length as to extend through an aperture provided in the extension 51 of the rail 33 and to extend above the latter, the part thus so extending being provided with an aperture or slot 49^a. On the rail 33 is secured a plate 52 by means of screws or bolts 52^a and 52^b. This plate carries a pivot 53 to which is pivoted a latch or hook member 54 having a locking tongue 54^a adapted to be swung into a slot or aperture 49^a and a finger piece 54^b. The member 54 may be swung to one side to relieve the tongue 54^a from the slot 49^a in member 49 for unlocking, and to the position shown in Fig. 2 for locking when the tongue 54^a extends through the slot 49^a.

This application is a division of my co-pending application Serial No. 646,761, filed June 21, 1923.

Having now described my invention, I claim:

1. A window construction comprising two sashes forming opposed meeting rails, each rail comprising an integral sheet of metal bent to provide a hollow main rail portion 10 and having a double fold forming a projection and a reentrant fold forming a seat spaced from the projecting fold whereby to receive between said projections and reentrant folds the edge of the window glass, 15 said reentrant fold receiving a window strip therein and said strip being arranged to cooperate with the projecting fold to secure the window glass in position on said rail, and said rail having an extension formed to 20 provide an upstanding portion spaced from the main portion of the rail and forming an intervening well or seat adapted to receive a downwardly extending projection upon the adjacent meeting rail.

2. A window construction comprising two sashes having opposed meeting rails, each rail comprising a sheet of metal bent to provide a hollow main portion having on one side spaced folded projection and reentrantly 30 folded portion forming a seat for the edge of the window glass and having on adjacent sides inward extensions of folded metal adapted to overlap when the window sashes are closed, one of said inward extensions being folded to form a well or seat and the other having a projection adapted to project thereinto.

3. A window construction comprising an 40 integral sheet of metal folded to form a hollow meeting rail formed with a folded projection and a folded reentrant portion spaced therefrom to form a seat for the window glass, a strip having a flange seating in the reentrant fold to hold the glass in position, the adjacent portion of the rail being folded to project laterally to form the portion of the rail that is adapted to overlap with another portion of the opposite rail.

4. In a window construction, a sash comprising a rail provided with a rabbet against which one side of a pane may engage, and a groove in the rail near the opposite face 55 of the plane, and a stop for the pane, said stop comprising a strip of sheet metal having an intermediate shoulder and side flat portions, one of said side portions being adapted to extend into said groove with the 60 shoulder in engagement with the rail and the other portion resting flat against the pane.

5. In a window construction, a sash pane 65 stop comprising a strip of sheet metal having a longitudinal pressed-out rib intermedi-

ate the width of the strip, and flat portions at the sides of the rib.

6. In a window construction, a sash pane stop comprising a strip of sheet metal having a longitudinal pressed-out rib intermediate the width of the strip, and flat portions 70 at the sides of the rib, said flat portions lying in different parallel planes.

7. In a window construction, a sash pane stop comprising a strip of sheet metal having a longitudinal pressed-out rib intermediate the width of the strip, and flat portions 75 at the sides of the rib, said flat portions lying in different parallel planes, a medial U-shaped rib and laterally extending flat flanges disposed in parallel planes. 80

8. In a window construction, the combination of sheet-metal rails disposed in rectangular formation and having folded portions providing inwardly extending flanges 85 and outwardly extending grooves or pockets with intermediate seats for the edges of the glass, sheet-metal stops for holding the glass in position, each stop having a tongue projecting outwardly into the pocket of its corresponding rail and each stop having a reversely extending resilient flange pressing against the side of the glass, the adjacent stops at two corners having beveled edged junctions, and one of the stops having edges 90 disposed parallel to the inner longitudinal edges of the adjacent stops and of a length to nicely fit therebetween, and means passing through the tongue of said last mentioned stop and its rail for detachably securing said stop in position and whereby to hold all of the stops in position without further fastening means.

9. In a window construction, the combination of sheet-metal rails disposed in rectangular formation and having folded portions providing inwardly extending flanges and outwardly extending grooves or pockets 95 with intermediate seats for the edges of the glass, sheet-metal stops for holding the glass in position, each stop having a tongue projecting outwardly into the pocket of its corresponding rail and each stop having a reversely extending resilient flange pressing against the side of the glass, the adjacent stops at two corners having beveled edged junctions, and one of the stops having edges 100 disposed parallel to the inner longitudinal edges of the adjacent stops and of a length to nicely fit therebetween, and means passing through the tongue of said last mentioned stop and its rail for detachably securing said stop in position and whereby to hold all of the stops in position without further fastening means. 105

form a rabbeted part for the seating of a pane of glass, said strip being further bent to provide a pair of laterally adjacent grooves.

5 11. In a window construction, a sash rail comprising a strip of sheet metal bent to form a rabbeted part for the seating of a pane of glass, the inner edge of said strip being bent upwardly and folded upon itself to provide a groove, said inner edge being further bent to provide another groove.

10 12. In a window construction, a sash rail comprising a strip of sheet metal bent to form an outer rabbeted part for the seating of a pane of glass, an inner groove for the reception of a tongue of an adjacent rail, and an intermediate groove for reception of a sash pane stop for retaining said pane in said rabbeted part.

15 13. In a window construction, an outer sash rail comprising a strip of sheet metal bent to provide a rabbeted part for the seating of a pane of glass, said strip being further bent to provide a groove for reception of a sash pane stop, the inner wall of said groove being substantially in the plane of said rabbeted part for engaging with a shoulder of said stop.

20 14. In a window construction, a sash rail comprising a strip of sheet metal bent to provide a rabbeted part for the seating of a pane of glass, said strip being further bent to provide an inner groove lower than said rabbeted part, and an intermediate groove between said rabbeted part and said lower groove.

25 15. In a window construction, a sash rail comprising a strip of sheet metal bent to provide a rabbeted part for the seating of a pane of glass, said strip being bent to provide a groove contiguous to said part for reception of a pane stop, the strip opposite said part being bent outwardly and downwardly.

30 16. In witness whereof, I hereunto subscribe my name to this specification.

FRANCIS J. PLYM.
